UNITED STATES PATENT OFFICE.

CARL O. JOHNSON, OF BRADFORD, PENNSYLVANIA, ASSIGNOR TO BRADFORD MACHINE COMPANY, OF BRADFORD, PENNSYLVANIA, A PARTNERSHIP CONSISTING OF CARL O. JOHNSON, HARRY SHEA, PAUL D. BONNER, H. W. QUINN, HARRY COONEY, AND E. G. FLAHERTY.

MACHINE FOR TRIMMING TENPINS.

Application filed November 29, 1926. Serial No. 151,437.

This invention relates to a machine for cleaning, polishing and truing bowling pins, the general object of the invention being to provide means for rotating a pin directly from a motor, with a combined centering and cupping tool carried by the tail stock ram for rotatably supporting the base of the pin and means associated with the ram for guiding a cutting tool to cause the same to true the body and base of the pin.

A further object of the invention is to provide an adjustable bumper or spacer on the ram for limiting the movement of the ram and the parts associated therewith toward the pin.

A still further object of the invention is to provide means for locking the ram in its adjusted position.

Another object of the invention is to make the tool holder slideable on the form or guiding means, carried by the ram, so that the tool will be brought into contact with the lower part of the body and the bottom end of the pin.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is an elevation of the device in use.

Figure 2 is a plan view with parts broken away.

Figure 3 is a section on line 3—3 of Figure 2.

Figure 4 is a section on line 4—4 of Figure 2.

Figure 5 is a sectional view through the clutch for connecting the top end of the pin with the motor.

Figure 6 is a face view of Figure 5.

Figure 7 is an enlarged fragmentary top plan view of the front end of the ram and the parts associated therewith.

Figure 8 is a section on line 8—8 of Figure 7.

Figure 9 is a section on line 9—9 of Figure 7.

Figure 10 is a section on line 10—10 of Figure 7.

In these views, 1 indicates the base of the machine which supports at one end a motor 2 and at its other end the stand 3 for the tail stock ram 4 which is slidably mounted in the guideways 5 horizontally arranged in the top of the stand. This ram is reciprocated by means of the hand lever 6 which is pivotally connected with the bottom of the stand and is connected with the rear part of the frame by a pin 7 which passes through a slot 8 in the lever. A shaft 9 is threaded in the top part of the stand 3 and passes through a hole in a part of the guideway, this part being weakened at 10 so that the weakened part will engage the ram and thus frictionally hold it against movement. The upper end of the shaft is provided with a handle 11 by which it may be turned.

The front end of the ram carries a centering pin 12 and a cutting tool 13 which is so shaped as to engage the cup-shaped recess in the bottom of the pin A while the pin 12 is engaging the center hole of said pin. A bumper or stop plate 14 is adjustably connected with this end of the ram by the bolts 15 engaging threaded holes in the ram and passing through slots 15' formed in the plate. This plate will engage the end of the pin A and thus prevent further movement of the ram. A form or guiding arm 16 is connected with the forward end of the ram at one side thereof and this arm comprises a curved forwardly extending part 16' and a straight portion 16'' which is provided with an extension 16*. The outer edge of the two parts of this arm is formed with a groove 17 which provides a tongue which engages a groove 18 formed in the tool holder 19 so that the said holder is slidably connected with the arm. The holder is engaged with the tongue of the arm by pushing it over the tongue of either the part 16' or the extension 16*.

The holder has a handle 20 at one end and a plate 21 is fastened to the body by a bolt

22, a pin 23 carried by the body and engaging a hole in the plate preventing rotary movement of the plate on the bolt. This plate acts to clamp a tool such as shown at 5 24 in place in a recess in the body of the holder. As will be seen, the tool extends over the guiding arm and engages the pin A and by moving the holder over both portions of the arm, the tool will be caused to 10 engage the body of the pin and the bottom end thereof, Figure 2 showing the tool engaging the bottom in full lines and the body in dotted lines. By adjusting the stop plate 14 on the ram, the amount of material moved 15 from the pin by the tool can be controlled. Of course, the arm 16 is so formed that the tool will be so positioned that it will true the body and the bottom of a pin and clean and polish the same. A leg 25 is fastened 20 to the outer end of the arm 16 to support the same from the base.

The means for supporting the top end of the pin and for rotatably connecting it with the motor comprises a clutch device which 25 consists of a metal cup 26 which has its neck fastened to the shaft of the motor 2 and a cup-shaped member 27 formed of rubber or the like which is held in the cup 26 by the screw 29. This block 28 is provided with 30 a semi-spherical socket 30 and the inner wall of the resilient cup 27 is formed with an annular shallow groove 31. This resilient cup will act to pull the top end of the pin A into the clutch until its end engages the 35 socket 30 and thus properly position the pin and cause it to rotate on its axis.

From the foregoing it will be seen that a pin can be easily placed in the device by drawing the ram 4 to the rear by the lever 40 6 so that a pin can have its head placed in the clutch and then the ram is moved forwardly until its pin 12 engages the hole in the bottom of the pin. The stop plate 14 is then adjusted to space the ram and 45 the arm 16 a sufficient distance from the pin so that the tools 13 and 24 will engage the pin to cut therefrom a sufficient amount of material to clean and polish the same and to true the pin. The tool holder 19 is moved 50 over the part 16' to true the body of the pin and then it is pushed over the extension on to the part 16'' to true the bottom of the pin. The tool 13 will cut the walls of the recess in the bottom of the pin.

55 This tool will bring a pin to its original standard diameters of both the body and base and the pin can be operated on again and again until its height is reduced beyond the height called for by the regulations.

It is thought from the foregoing description that the advantages and novel features of my invention will be readily apparent.

I desire it to be understood that I may 65 make changes in the construction and in the

combination and arrangement of the several parts, provided that such changes fall within the scope of the appended claims.

What I claim is:—

1. A machine for trimming bowling pins 70 comprising a motor, a friction clutch connected with the shaft thereof for engaging the head of a bowling pin to be operated on by the machine, a support, a reciprocatory member carried thereby, a centering pin carried by the member for engaging a hole in the base of the bowling pin, a guiding arm carried by the reciprocatory member and including a curved part and a straight part and a tool holder adapted to be moved over both the curved part and the straight part of the arm to bring its tool in engagement with the sides and base of the bowling pin.

2. A machine for trimming bowling pins 85 comprising a motor, a friction clutch connected with the shaft thereof for engaging the head of a bowling pin to be operated on by the machine, a support, a reciprocatory member carried thereby, a centering pin carried by the member for engaging a hole in the base of the bowling pin, a guiding arm carried by the reciprocatory member and including a curved part and a straight part, a tool holder adapted to be moved over both the curved part and the straight part of the arm to bring its tool in engagement with the sides and base of the object, a stop plate on the reciprocatory member for engaging the bowling pin to limit the inward movement of the reciprocatory member and its guiding arm.

3. A machine for trimming bowling pins 105 comprising a motor, a friction clutch connected with the shaft thereof for engaging the head of a bowling pin to be operated on by the machine, a support, a reciprocatory member carried thereby, a centering pin carried by the member for engaging a hole in the base of the bowling pin, a guiding arm carried by the reciprocatory member and including a curved part and a straight part, a tool holder adapted to be moved over both the curved part and the straight part of the arm to bring its tool in engagement with the sides and base of the bowling pin and a cutting tool at one side of the centering pin for engaging the walls of a recess formed in the base of the bowling pin.

4. A machine for trimming bowling pins 120 comprising a motor, a friction clutch connected with the shaft thereof for engaging the head of a bowling pin to be operated on by the machine, a support, a reciprocatory member carried thereby, a centering pin carried by the member for engaging a hole in the base of the bowling pin, a guiding arm carried by the reciprocatory member and including a curved part and a straight part, a tool holder adapted to be moved over both the curved part and the straight part of the arm to bring its tool in engagement with the sides and base of the bowling pin.

5 moved over both the curved part and the straight part of the arm to bring its tool in engagement with the sides and base of the bowling pin, a cutting tool at one side of the centering pin for engaging the walls of a recess formed in the base of the bowling pin and a stop plate on the reciprocating member for engaging the bowling pin to limit the inward movement of the reciprocating member and its guiding arm.

5. A machine for trimming bowling pins comprising a motor, a friction clutch connected with the shaft thereof for engaging the head of a bowling pin to be operated on by the machine, a support, a reciprocating member carried thereby, a centering pin carried by the member for engaging a hole in the base of the bowling pin, a guiding arm carried by the reciprocating member and including a curved part and a straight part, a tool holder adapted to be moved over both the curved part and the straight part of the arm to bring its tool in engagement with the sides and base of the bowling pin and means for locking the reciprocating member in adjusted position.

6. A machine for trimming bowling pins comprising a base, a motor supported at one end of the base, a stand supported at the other end of the base and having a guideway in its top, a ram slidably mounted in the guideway, a lever for moving the ram, means for locking the ram in adjusted position, a guiding arm connected with the forward end of the ram, and including a straight portion which is connected with the ram and a curved forwardly extending portion, a tool holder adapted to be moved over each portion of the arm, a tool carried by the holder, a centering pin at the front end of the ram, a curved cutter associated with the pin, a stop plate connected with the ram and adapted to engage a bowling pin being operated upon by the machine to limit the forward movement of the ram and a resilient holder for one end of a bowling pin connected with the motor shaft, the other end of the bowling pin having a hole therein for receiving the centering pin.

50 7. In a pin trimming machine, a driven shaft, work engaging means connected therewith, supporting means, a slidable element carried by the supporting means, work centering means controlled by the slidable element, and tool mounting means positioned simultaneously with the movement of the slidable element and including members for supporting the tool for movement along the side of the work and transversely of the longitudinal axis thereof.

8. In a pin trimming machine, a driven shaft, work engaging means connected therewith, supporting means, a slidable element carried by the supporting means, work centering means controlled by the slidable ele-

ment, and tool mounting means positioned simultaneously with the movement of the slidable element and including members for supporting the tool for movement along the side of the work and transversely of the longitudinal axis thereof, and means for retaining the tool mounting means in an adjusted position.

5 9. In a pin trimming and polishing machine, work engaging means, means for rotating same, a slidably mounted element, operating means therefor, mounting means positioned simultaneously with the movement of the slidable element and including portions for supporting a tool for movement along the sides of the work and transversely of the main axis thereof.

10. In a pin trimming and polishing machine, yielding work engaging means, means for rotating same, a slidably mounted element, operating means therefor, mounting and guiding means positioned incident to the movement of the slidable element and including portions for supporting an operating element for movement in two directions with reference to the main axis of the work.

11. A machine for trimming bowling pins comprising a motor, a friction clutch connected with the shaft thereof for engaging the head of a bowling pin to be operated on by the machine, a support, a reciprocating member carried thereby, a guiding arm carried by the reciprocating member, said arm having a curved path and a tool holder adapted to be moved over the curved path to bring its tool into cutting engagement with the sides of the bowling pin.

12. A machine for trimming bowling pins comprising a motor, a friction clutch connected with the shaft thereof for engaging the head of a bowling pin to be operated on by the machine, a support, a reciprocating member carried thereby, a guiding arm carried by the reciprocating member, said arm having a curved path thereon, a tool holder adapted to be moved over the curved path to bring its tool into cutting engagement with the sides of the bowling pin and a stop carried by the reciprocating member for engaging the bowling pin to limit the inward movement of the reciprocating member and the guiding arm.

13. In a machine for trimming bowling pins, the combination of a head chuck for gripping the head of the pin, a motor for rotating the head and pin, a stationary tailstock, a member carried by said tailstock and movable with relation thereto and a tool guide movable with said member into a predetermined position.

14. In a machine for trimming bowling pins, the combination of a head chuck for gripping the head of a pin, a motor for rotating the chuck and pin, a stationary tailstock, a member carried by said tailstock

- and movable with relation thereto, a tool guide movable with said member and means movable with said member and said guide for limiting the movement thereof.
15. In a machine for trimming bowling pins, the combination of a chuck for gripping the head of a pin, a motor for rotating the chuck and pin, a support, a member carried by said support and movable with relation thereto, a tool guide carried by said member and movable therewith, and means movable with said member and said guide and adapted to abut the base of a pin for limiting the movement of the guide.
16. A machine for trimming bowling pins comprising a clutch for gripping the head of a bowling pin, a motor for rotating the clutch and bowling pin, a support and a centering pin carried by said support, in combination with a reciprocatory tool guide carried by said support.
17. A machine for trimming bowling pins comprising a clutch for gripping the head of a bowling pin, a motor for rotating the clutch and bowling pin, a support and a centering pin carried by said support, in combination with a reciprocatory tool guide carried by said support and a reciprocatory stop carried by said support for limiting the movement of said tool guide.
18. A machine for trimming bowling pins comprising a motor, a clutch connected with the shaft thereof for engaging the head of a bowling pin to be operated on by the machine, a support, a reciprocatory centering pin carried by said support, a tool holder, a guide for forcing said tool holder to follow a predetermined path and means whereby said guide may be made to assume a predetermined position with relation to the base of the bowling pin.
19. In a machine for trimming bowling pins comprising a motor, a rotatable clutch for holding the head of a bowling pin, and a centering pin; the combination of a tool holder, means cooperating with said tool holder to guide same along a radial path for trimming the base of a pin, means cooperating with said tool holder to guide same along a curved path for trimming the face of a pin, and means for variably positioning the first and second named means.
20. In a machine for trimming bowling pins comprising a motor, a rotatable clutch for holding the head of a bowling pin, and a centering pin; the combination of a tool holder, means cooperating with said tool holder to guide same along a radial path for trimming the base of a pin, and means cooperating with said tool holder to guide same along a curved path for trimming the face of a pin.
21. In a pin trimming machine comprising a driven shaft and work engaging means connected therewith; the combination of a tool holder and longitudinally slidable means cooperating therewith to guide the tool holder for movement along the sides of the work for trimming the face of the pin and transversely of the main axis thereof, for trimming the base of the pin, whereby the tool holder may be guided along two independent paths successively by an intermediate shifting of the position of the tool holder.
22. In a pin trimming machine comprising a driven shaft and work engaging means connected therewith; the combination of a tool holder, means cooperating therewith to guide the tool holder for movement along the sides of the work and transversely of the main axis thereof, whereby said tool holder may be guided along two independent paths successively by an intermediate shifting of the position of the tool holder, and means for variably positioning said first named means with relation to the base of the pin along a line parallel to the axis of the work.

In testimony whereof I affix my signature.
CARL O. JOHNSON.
